DEVICE FOR DRYING CONTAINERS
INTERNAL

Albert Loacker, Bregenz, Austria

Application August 29, 1932, Serial No. 630,959

2 Claims. (CL. 34—18)

My invention relates to a drying apparatus and more particularly to devices which are used for drying containers internally, such as milk cans, barrels, bottles and the like, also which may be used for drying the internal structures of walls of vessels, vats, bins or devices, construction of which will not permit the interior of such structures to be dried and relieve it from moistures by any other means.

10 It, accordingly, is an object of my invention to provide an apparatus of simple construction which may be easily handled or permanently positioned in a place where its function may be most desirable in practice, and which is preferably operated by an electrically driven motor or some other suitable means, having a fan attached thereto and through its rapid rotation creating an air current which is permitted to pass into a concentrator wherein a plurality of electrically heated elements are positioned, thus creating a blast of hot air at the tapered end or mouthpiece of said concentrator and to provide a shell surrounding the concentrator in spaced relation thereto together with a construction whereby air exhausted from a container may be directed into said shell.

The above, and further objects and advantages of my invention as will hereinafter more fully appear, I attain by the construction shown and described in this specification and illustrated on the drawings forming a part of my application.

Reference is had to the accompanying drawings in which the reference characters denote similar parts.

35 In the drawings:

Fig. 1 is the elevational view of the hot air producing apparatus.

Fig. 2 is the cross-sectional view taken on the line 2—2 of the Fig. 1.

40 Fig. 3 is the transversal and cross-sectional view taken on the line 3—3 of the Fig. 2.

Fig. 4 is the cross-sectional view taken on the line 4—4 of the Fig. 3.

Fig. 5 is the cross-sectional view taken on the line 5—5 of the Fig. 3.

Fig. 6 shows the construction of the shaft shown in the cross-section, Fig. 3.

Fig. 7 shows the means of holding the elements upon the shaft.

50 Fig. 8 is the cross-sectional view of the mouthpiece attachment.

Fig. 9 shows the end view of said attachment.

Fig. 10 is partly cross-sectional and partly elevational view showing means of attaching a flexible tube to the mouthpiece of the apparatus.

Fig. 11 is a view in longitudinal section with parts in elevation showing a modified form of the invention:

Fig. 12 is a view in cross section taken on the line 12—12 of Fig. 11: 5

Fig. 13 is a detail in cross section taken on the line 13—13 of Fig. 11:

Fig. 14 is a view in cross section as seen on the line 14—14 of Fig. 11;

Fig. 15 is a view of the apparatus as seen on the line 15—15 of Fig. 11:

Describing my invention more in detail, said invention comprises of a housing A which is adapted to receive a motor 4 at one end, having a cover associated therewith as at 6 and the opposite end 15 of said housing is adapted to receive a concentrating drum 8, preferably smaller in diameter and terminating with a conically shaped mouthpiece 10, as shown.

Carried on the housing A is a shell 2 having 20 a tapered outer end portion 12 and which shell is concentrically spaced from the drum thereby forming a chamber 14 between the drum and the shell. Formed on the outer end of the tapered portion 12 of the shell, is a conically shaped end 25 piece 16 which encloses the mouth piece 10 with its reduced end margin spaced from said mouth piece thereby forming an opening around the mouth piece communicating with the chamber 14. The end of the tapered conical end piece 16 is 30 spaced inwardly from the end of the mouth piece.

Internally within said drum 8, I have positioned a plurality of elements 18 which may be of any desired configuration and are mounted upon a hollow shaft 20 held in place by means of a collar 22 locked by a split washer 24, permanently located in the groove 26, having spacing collars 28 positioned therebetween and locked in place by means of a nut 30, as shown in Fig. 3. 35

Said shaft 20 is secured to a center section 40 32 comprising a hub 34 wherethrough said shaft 20 protrudes and is held in place by means of a split locking collar 36; said center section 32 is provided with a plurality of air circulating holes 38 having an apron 40 equipped with a plurality 45 of slots 42, extending inwardly into the chamber 44 wherein the air pressures are created by means of a fan 46, driven by said motor 4, having the inlet air holes 48 positioned as shown.

The concentrating drum 8 is also equipped with 50 a flared out base section 50 which insulates said drum 8 from the chamber 44 and the cooling shell 2, which is also equipped with holes 52 which holes may serve either as warm air outlets or cold air inlets. 55

The drum 8 is also equipped with a heat retaining means 53, such as asbestos or other material most desirable in practise, which is for the purpose of preventing the radiation of heat from such shell 8 into the chamber 14.

In the Fig. 8, I have shown an extension shell 54, preferably of tapered construction which comprises a shell 56, the base flange 58 which is used for attaching it to the end piece 16, having the nozzle 60 terminating with a protector 62, comprising strip 64 attached as shown.

Internally within said shell 54, I have positioned a centralizing ring 66 which may be of any desired length or width and which is for the purpose of holding said extension shell 54 in place, and by reason thereof extending the hot air currents beyond the mouthpiece 10, thus creating a concentrated hot air pressure at the opening 68 and a very effective vacuum, which draws the cool air through the holes 52, through the space 70, around the drum 8 and within said cooling shell 12.

In the event it may be desirable to extend the mouthpiece 10 for the purpose of heating or to direct the hot air in places not easily accessible, I have provided said extension 54, and the nozzle 60, with a binder 72 which is for the purpose of holding a flexible hose 74, or other tubing material in place, and which may be substantially secured to said nozzle 60 by means of a clamp 76 as shown in Fig. 10.

The housing A is also provided with a handle 78 so that the apparatus may be carried easily from place to place and in order to place said apparatus in a convenient position, I have provided it with legs 80 which may be of any desired shape and may be, if preferred, used for attaching said apparatus to a floor, walls or the like.

The apparatus is also provided with a switch 40 82 which makes the contact between the motor 4 and the heating elements 18 which are connected in series by means of lead wire 84.

In operation, the fan 46, turning at high speed, draws the air into the chamber 44 through the inlet openings 48, forcing it against the base section 50 and between the slots 42 of the apron 40, passing through the openings 38 within the drum 8 circulating around said elements 18 and emerging at the mouthpiece 10 and when the end piece 16 is inserted in an opening of a vessel or a barrel, as the case may be, the draft or blast of hot air passing through said mouthpiece 10 will effect displacement of air within the vessel or barrel and cause such displaced air to flow to discharge from the interior thereof around the mouth piece 10 and into the end piece 16 through the passage 14 and through the holes 52. In event the extension shown in Fig. 8 is employed the hot air discharging from the mouth piece 10 will effect reversal of flow of air through the passage 14 as before stated and in this instance the displaced air from the vessel or barrel will be permitted to flow to atmosphere around the tapered shell 54.

In Fig. 12, the tapered mouth piece 18 is shown as formed with a tubular extension 85 and carried on said extension in spaced relation to the outer end thereof is a cone fitted with fins 86 which cone is tapered to be inserted in the bung hole of a barrel and with the fins contacting the margin of the hole whereby displaced air may be caused to flow between the fins 86 and into a cylindrical projection 87 on the mouth piece 16 of the shell 2 and into the passage 14 and out 10 the openings 52. Also in the construction shown in Fig. 12 the drive shaft 89 of the fan or blower 46 is connected to the drive shaft of the motor through a conventional clutch 90. The shell 2 may be lined with an insulating material indicated at 91 between which and the drum 8 a spacing member 92 is interposed.

While I have thus described my invention with great particularity, it will be clear that the same may be modified throughout a wide range. I, accordingly, do not propose to be limited to the exact details of construction as shown and described in this specification and reserve the rights in practice to make any and all modifications which may come within the scope of the appended claims.

I claim as my invention:

1. In a device for drying the interiors of barrels and like containers, a portable housing, a motor in said housing, a drum carried by said housing and communicating at its inner end with the interior thereof, a mouth piece on the outer end of said housing adapted to be inserted in an opening in a container, an electrical heating element in said drum, a fan in said housing operated by said motor to impel a stream of air through said drum and into a container through said mouth piece, a shell encircling said drum in spaced relation thereto and fixed at its inner end to said housing, said shell having an open outer end spaced inwardly from the discharge end of said mouth piece; the outer end of said shell adapted to be positioned to receive the displaced air discharged from the container.

2. A portable device for drying the interior of containers comprising a housing having a fan chamber, a fan in said chamber, a motor in said housing operatively connected to said fan, a cylindrical drum protruding from said housing opening at one end to said fan chamber, a mouth piece on the outer end of said housing insertable in an opening in a container, an electrical heating element in said drum, a tapered conical element carried on said mouth piece having fins engageable with the margin of the opening of the container to permit the flow of displaced air from the interior to the exterior of said container around said end piece, and a shell surrounding the part of the drum adjacent the opening of the container in spaced relation thereto having an open end adjacent said conical end piece to receive air discharged around said conical end piece.

ALBERT LOACKER.
